HIGH VOLTAGE FUSIBLE CUT-OUT

George Leslie Hill, Oakland, Calif.

Application November 26, 1934, Serial No. 754,747

32 Claims. (Cl. 200—120)

This invention relates to a high voltage fusible cutout, and particularly to improvements in fusible cutouts of the type disclosed in my co-pending applications entitled "High tension fuse", filed July 9, 1928, Serial Number 291,214, and "High tension fuse", filed January 12, 1931, Serial Number 508,029. It also relates to improvements whereby the fuse device is combined with an enclosed manually operated switch for installation in subways, vaults, basements etc., which may be damp, or flooded with water at times, or installations where gases expelled might ignite explosive vapors and cause an explosion.

15 All enclosed underground, high voltage, fusible cutouts available and known at the present time use oil for an insulating medium and a fusible element immersed in the oil for interrupting overcurrent. The fuses used in enclosed, fusible cutouts are of three general types:

20 (a) Expulsion type, consisting of a long tube of insulating material, open at both ends, and having metal ferrules pressed onto the ends of the tube. A copper or alloy fuse element passes through the tube and is fastened to each ferrule. The fuse tube is clamped onto an operating arm which is used to engage or disengage the fuse with terminals in the cutout. A cutout box is employed which is filled with oil, and this oil 25 fills the fuse tube and entirely surrounds the fuse element.

25 (b) Spring actuated type in which the fuse element consists of an alloy strip with a strain wire, connected in parallel with the strip, to relieve the alloy strip of the tension from the spring. The fuse element and attached spring are inserted in an insulating tube, with metal end caps, the element being fastened to one cap and the spring to the other. The tube is divided into 30 two chambers by a center partition with a hole through it. The fuse element is disposed in one chamber, which becomes the explosion chamber, and the spring is disposed in the adjacent chamber, which becomes the expansion chamber, the 35 expansion chamber being in turn vented to the inside of a cutout box. The cutout box, in turn, is filled with oil and the oil fills the fuse tube and entirely surrounds the fuse element.

40 (c) Magnetic repulsion type in which the fuse element consists of a U-shaped member, fastened on the end of an insulated bayonet type plug which is inserted into the top of the cutout and then turned 90° for engaging or disengaging the 45 fuse with terminals in the cutout box. This box 50

is also filled with oil and the oil entirely covers the fuse element.

5 All of the types (a, b and c) have very definite disadvantages. As an example, the fuse tube and fuse element of the expulsion type is 5 ten or twelve inches long and the fuse element volatilizes throughout its entire length on large currents. The arc energy liberated is practically proportional to its length, so it may be seen that the arc energy liberated is very high. The 10 high pressure bursts the organic insulating tube and, in turn, burst the cutout box. On moderate over-currents the arc melts the fuse element and follows back to the ferrule and burns the tube and in some cases causes failure.

15 It has been found that the spring actuated type does not efficiently utilize the oil in the explosion chamber for the extinction of the arc, and also that the spring actually retards and hinders the operation of the device on heavy over-currents, rather than being an aid in the operation.

20 The link of the magnetic repulsion type is blown under oil in the main chamber of the cutout box and on large over-currents very high pressures are set up of the order of six hundred to twelve hundred pounds per square inch. Such pressures may be disastrous to the cutout box itself and to the supporting insulating members within the cutout box. Also on heavy over-currents, the magnetic repulsion actuates the 25 side bands of the U so rapidly that they strike the wall of the cutout box and rebound to the center and re-establish the circuit.

30 The insulation on the operating mechanism for supporting the fuse of all the types have been made of various organic materials, such as wood and moulded or laminated bakelite. It has been found that the small leakage currents over the 35 surface of these insulators made of organic material carbonizes a path and frequently causes a power arc to start and thereby results in failure of the device.

35 The object of the present invention is to provide an improved economical and efficient fuse device for the interruption of over-currents in an electric circuit; to provide an improved fuse cartridge for insertion in a circuit-interrupting device and to form the wall of the explosion chamber of metal so that it may function both 40 as a conductor for the circuit passing through the interrupting device, and, further, to function as a reinforcing member to sustain the high pressures generated when the fuse blows on heavy over-currents; to provide an improved and effi- 45 50 55

cient de-ionizing and cooling means for de-ionizing and cooling expelled gases, upon blowing of the fuse, whereby a dry type fuse device may be used within an enclosed cutout box; to provide an improved fuse cartridge for insertion in a fuse device, which is adapted to employ oil as the arc extinguishing medium, said fuse cartridge and device being adapted to be placed in a cutout box and to be submerged in oil; and, further, to provide means to prevent excessive arcing at the switch blades when utilizing the cutout as a disconnecting switch without using insulating oil in the cutout box.

The invention is shown by way of illustration 15 in the accompanying drawings, in which—

Fig. 1 is a longitudinal section of a fuse housing, showing a fuse cartridge mounted therein.

Fig. 2 is a longitudinal section of a fuse cartridge of a type filled with a dry granular or 20 powder material.

Fig. 3 is a longitudinal section of a fuse cartridge of the oil or liquid filled type.

Fig. 4 is a detail view of the lower end of the 25 fuse housing showing a modified form of the same.

Fig. 5 is a vertical, longitudinal section of the cut-out box, showing the fuse device and switch mechanism mounted therein.

Fig. 6 is a plan section, taken on line VI—VI of 30 Fig. 5.

Fig. 7 is an end view of the cutout box.

Fig. 8 is a vertical cross section, taken on the line VIII—VIII of Fig. 5.

Referring to the drawings in detail, and particularly Figs. 1 and 2, 2 indicates an elongated, 35 tubular member constructed of a suitable insulating material. This tube will hereinafter be referred to as the "cartridge tube". Disposed within the cartridge tube is a tube 3. This tube is constructed of metal and serves the following 40 functions: First, that of a conductor for the current passing through the fuse device; second, that of a receptacle for an arc extinguishing medium, such as indicated at 3a; and, third, that of a reinforcing member for the cartridge tube to sustain the high pressure developed during the blowing of the fuse during the interruption of the circuit.

Disposed at opposite ends of the cartridge tube are bushings 4 and 4a, which are constructed of a suitable insulating material, and carried by the respective bushings are copper or similar terminal members 5 and 5a. To the inner ends are soldered, or otherwise secured, fuse elements 6 and 6a. The opposite ends of the tube 3 are tapered to form annular seats for the reception of the insulating bushings 4 and 4a. The inner ends of these bushings are similarly tapered, and each bushing carries a tapered sleeve or ferrule 7 and 7a which is pressed on or otherwise secured thereto. These ferrules are in turn provided with an inwardly projecting tongue 8 and 8a, and the ends of the fuse elements 6 and 6a are soldered or otherwise secured thereto. The terminal member 5 terminates in a head 5b which is engaged by a cap 9. There is a screw connection 10 between the cap and the cartridge tube 2; hence when the cap is applied, endwise pressure is exerted on the terminal member 5 and the insulating bushing in which it is mounted and the ferrule is thus pressed downwardly into the tapered end of the tube 3 so as to form a contact for the conduction of current from the cap 9, through the terminal 5 and the fuse 6, to the tube 3.

The insulating bushing 4a is similarly tapered 75 on its inner end and carries a sleeve or ferrule 7a

provided with an inwardly extending tongue 8a, to which the fuse element 6a is soldered, or otherwise secured. The lower end of the terminal member 5a is enlarged, as shown at 5b, and extends through a stuffing box containing a packing 5 11 which is held in position by a nut 12, outside of which is applied a sealing medium 13. The insulating bushing 4a seats on an annular shoulder 14, formed at the lower end of the cartridge tube, and a good contact is formed between the ferrule 7a and the tube 3 when the cap 9 is applied, as the pressure exerted during the application of the cap does not only force the bushing 4, together with its ferrule 7 into the upper tapered end of the tube 3, but it also forces the lower tapered 10 end of the tube 3 downwardly against the ferrule 7a.

The device described is known as a fuse cartridge and it is adapted for insertion in a fuse housing (see Fig. 1). This housing consists of 20 a tube 15 constructed of a suitable insulating material. A ferrule 16 is screwed, or otherwise secured, on the upper end of the housing member 15 and a threaded extension 17 is provided to receive a closure cap 18. This cap engages the cap 9 and an electric circuit is thus formed between the ferrule 16 and the upper end of the fuse cartridge mounted within the housing. The lower end of the housing 15 is provided with a ferrule 19, threaded or otherwise secured thereto, and 30 this is provided with a threaded extension 20, in which is formed a pair of slots. This threaded extension performs two functions: First, that of securing a pigtail connection 21; and, secondly, that of supporting a gas de-ionizing and cooling 35 device, generally indicated at 22. The ends of the pigtail are placed in the slots formed in the extension 20, and when the device 22 is screwed on, the pigtail becomes clamped to the ferrule 19, thus forming an electric connection therewith. 40 The opposite end of the pigtail is soldered or otherwise secured to the enlarged extension 5b of the terminal 5a.

The fuse cartridge shown in Fig. 2 is known as 45 a dry type of fuse cartridge as the chamber formed between the fuse elements 6 and 6a is preferably filled with a relatively dry arc extinguishing medium in the form of powder granules, or cake, for instance, calcium carbonate, or any suitable 50 substance that acts as a de-ionizing agent when projected into the arc.

In Fig. 3 a modified form of fuse cartridge is shown which will be known as the wet or liquid type of fuse cartridge, as the arc extinguishing 55 medium employed may be an insulating oil, petroleum jelly, carbon tetrachloride, or other suitable material. In this instance the cartridge tube is indicated at 25. It is constructed of metal throughout and is threaded at opposite ends to receive insulating bushings 26 and 27. A terminal member 28, having a cap 29 at its upper end, is screwed into the upper end of the bushing 26. It carries a fuse element 30 and this is soldered, or otherwise connected, with a metal 65 bushing 31, screwed or otherwise secured in the lower end of the bushing 26. The bushing 31 makes contact with an annular shoulder 32 formed in the tube 25. An annular shoulder 33 is formed in the lower end of the tube 25 and a 70 diaphragm constructed of a suitable conducting material engages said shoulder, as indicated at 34, the diaphragm being held against the shoulder by means of a nut 35. A terminal member 36 is secured to the diaphragm and this is in turn con- 75

nected with a flexible conductor or pigtail 21a, similar to that disclosed in Figs. 1 and 2.

The diaphragm, indicated at 34, serves two main functions: First, that of a seal to retain the oil or other arc extinguishing substance with which the chamber, indicated at 38, is filled; and, secondly, it serves as a fuse. The diaphragm prevents leakage of the arc extinguishing substance employed around the terminal member 36 and by applying a suitable lacquer to the threads when the bushing 26 is applied leakage through that end of the fuse cartridge is avoided.

The fuse cartridge shown in Fig. 2, as previously described, is designed for insertion in the fuse housing, such as shown in Fig. 1. The wet or liquid type of cartridge shown in Fig. 3 is similarly suited for insertion in the housing 15, but the gas de-ionizing and cooling device, indicated at 22, will in that instance be removed and it will be replaced by a slotted cap, such as shown at 22a (see Fig. 4). The gas de-ionizing and cooling device, indicated at 22, is similar to the one shown in my co-pending application entitled "High tension fuse", filed January 25 12, 1931, Serial Number 508,029, but is an improvement thereon.

In my earlier disclosure of the device above referred to, a single chamber was employed, into which the gases from the cartridge discharge. The chamber was perforated and steel wool or a similar cooling medium was placed within the chamber. In the present instance (see Fig. 1) a central chamber 40 is provided and surrounding the same is an annular chamber 41. Two concentric tubular walls are provided, as indicated at 42 and 43. These are both perforated and the space between them is filled with steel wool or a similar cooling medium, the cooling medium being retained in the annular chamber by a bottom plate 44.

By this construction the hot gases discharged from the fuse cartridge are permitted to rapidly expand. This, obviously, aids in the cooling of the gases and as the gases also have to pass through the cooling medium in the annular chamber 41 further and rapid cooling of the gases is insured. If desired, the wall 43 may be used without any perforations, thus making an entirely closed in device.

While the dry type of fuse cartridge and the housing provided for it and shown in Fig. 1 may be placed wherever desired, I wish to emphasize the fact that it may also be placed in confined spaces, such as cutout boxes, and the like. The liquid or wet type of fuse cartridge, shown in Fig. 3, is one intended for installation in a cutout box, and its use will hereinafter be described.

For the purpose of describing the manner in which a fuse device of this character may be installed in a cutout box, reference will be made to Figs. 5 to 8, inclusive. In these figures the numeral 50 indicates a form of cutout box which is provided with two cables entering the cutout box through insulating bushings 51-51. Passing through the bushings and suitably secured therein are terminal studs 52, to which are fastened spring clip contacts 53. Switch blades 54 are adapted to be inserted between the contacts and they are secured to clamping members 55 which are, in turn, secured to and supported by porcelain insulators 56, these being secured, in turn, to an operating rod or shaft 57 by means of clamps 58. The switch blades 54 form a part of the clamping members 55 and they are fastened to the insulators 56 by cap screws or similar

means. The operating shaft 57 is supported in bearings, as shown, and one end extends through the end of the cutout box, the extending end being provided with an operating handle 59, on which is mounted a knob 60. The handle swings over a quadrant 61 and slots or depressions may be formed therein to retain the switch arm in different positions.

The housing 15 containing a fuse cartridge, whether it be of the dry or liquid type, is best shown in Figs. 6 and 8. It is secured at opposite ends by the clamping members 55 and as these surround the ferrules 16 and 19, a circuit through the switch and the fuse device is established.

To place the device in service, the operation will be as follows: The handle 59 is moved to the re-fuse position on the quadrant 61 and the fuse housing 15, containing a fuse cartridge, is inserted in the clamps 55 and secured therein and the handle is then moved to the open position. If a dry type of fuse cartridge is to be inserted the gas de-ionizing and cooling device, shown at 22, will be applied before the fuse cartridge is inserted. After that it will only be necessary to apply a cover on the cutout 50 and to clamp it down by the thumb-screws shown, a packing being interposed between the box and the cover to render the box watertight.

After the cover has been securely fastened, the handle 59 is moved to closed position. This causes engagement of the switch blades 54 with the spring contacts 53, thus placing the fuse in the electric circuit.

When an over-current occurs, the fuse element 6 will melt or blow first as it is purposely made smaller than the element 6a. The heat from the resultant arc will decompose the surrounding arc extinguishing substance and thereby generate a gas which will build up a high pressure in the chamber. When the pressure has reached a predetermined value, the terminal member 5a starts to move outwardly and places a tension on the fuse element 6a. When the tension exceeds the strength of the fuse element 6a, which, by the way, has already been weakened by the heat produced by the over-current, it is easily pulled apart, causing a secondary arc as the terminal 5a is expelled outwardly through the tube 4a. The tubes 4 and 4a, may be made of 50 a material, such as horn fibre, which will also decompose from the heat of the arcs and give off a de-ionizing gas.

The instant the secondary arc is established in the passage of the bushing 4a, the gases previously generated and the arc extinguishing substance are blasted into it at a high velocity and in a turbulent manner. This causes a rapid de-ionizing action to take place and interrupts the circuit. The gas blast from the chamber will 60 expel all the ionized products resulting from the arcs and leave a clean de-ionized path in the bushing 4a.

When the terminal member 5a is expelled from the fuse cartridge the flexible conductor or pigtail 21 is forced downwardly into the chamber 40 where it will pile up and introduce an insulated path between the end of the fuse cartridge and the interior of the ferrule 19. The hot ionized gases expelled from the central passage 70 in the bushing 4a will also pass into the chamber 40 and then through the perforated cylindrical wall 43 into the annular chamber 41 and then through the perforations in the outer wall 43. During this flow the gases expand and cool and 75

are finally released into the space within the cutout box.

Tests and experiments have been conducted which show that the expulsion and cooling of the gases are so thorough that they may be successfully released within an enclosed metal cutout box, such as here illustrated, making such boxes available for underground, subway or basement service. However, tests have also shown that the holes in wall 43 may be eliminated and the material in chamber 41 will continue to act as a cooling medium for the gases.

On large over-currents both fuse elements 6 and 6a will blow or melt, but due to the fact that the element 6 is smaller than the element 6a an increment of time will always exist between the blowing of the two fusible elements, the increment decreasing as the current increases but the blowing of the two elements will never become simultaneous, so that there will always be a pressure generated by the primary arc at 6 before the arc starts at 6a, this pressure being utilized to extinguish the second arc.

The secondary arc at 6a, while it persists, will also generate a gas by decomposing the surrounding arc extinguishing substance. This gas, due to the fact that the arc at 6a starts at a later period of time than the arc at 6, will be at a lower pressure than the gas from the arc at 6 and will be blasted back into the arc stream at 6a, resulting in a most efficient and quick means of interrupting the electric circuit.

In the ordinary operation of a switch, when the box is not filled with an oil, such as shown in Figs. 5 to 8, inclusive, it is obvious that excessive arcing will take place between the blades 54 and the spring contacts 53 whenever the switch is opened while carrying a load current. To reduce such a tendency to arc, a shunt circuit is here illustrated. This shunt circuit is established by providing a pair of auxiliary switch blades 70, which engage spring contacts 71. These contacts are fastened to a casting 72 by means of screws, as shown. A suitable resistance material 73 is clamped between the casting 72 and a bracket 14. The object of this auxiliary circuit is to aid in preventing excessive arcing when the cutout is used as a disconnecting switch without oil in the cutout box. The blade 70 and contact 71 are designed to remain in contact after the blades 54 and contacts 53 have parted, thus shunting the circuit from the main operating blades and contacts through the resistance material 73 and the blades and contacts, indicated at 70 and 71. The resistance material 73 employed in this instance may have a characteristic similar to the inorganic resistance material used in lightning arresters; that is, it is substantially an insulator at a low voltage and a conductor at a high voltage. The resistance material referred to is a dense synthetic granular compound of a refractory and a ceramic nature combined into a mass under high temperature. It is usually sold under the trade names 65 of "Thyrite", "Antovalve" and "Granulon".

When the voltage rises to its full value during an alternating current zero, while an arc is drawn between 54 and 53, the material 73 will become a conductor and shunt the current 70 around through the bracket 14, the resistance material 73, castings 72, contacts 71 and blades 70. The arc will then break easily between the contacts 53 and blades 54, and due to the additional resistance interposed in the shunt circuit, 75 the arc will also break easily between the contacts

71 and the blades 70, thus interrupting the circuit.

The cutout box, which has been described up to this point in conjunction with the dry type of cartridge fuse, has not been filled with an insulating oil, but above certain operating voltages the cutout box may be filled with oil and the dry type fuse cartridge is replaced with a fuse cartridge, utilizing oil, of the type illustrated in Fig. 3. The similarity in construction and operation between the dry type fuse cartridge and the liquid or oil type fuse cartridge is readily observed. It will be noted that an insulating tube, similar to that shown at 2 (see Fig. 2), is not employed as it has been found by tests to be unnecessary, due to the fact that the oil surrounds the fuse cartridge tube 25 when inserted in the housing tube 15 and thereby provides sufficient insulation. The housing tube 15 is, accordingly, used for both the dry and liquid type of fuse cartridge, and the only change necessary, when employing a liquid type of fuse cartridge, is to remove the gas de-ionizing and cooling member, indicated at 22, and replace it with the slotted or perforated cap, shown at 22a in Fig. 4. This cap is nothing more nor less than a venting cap and it is employed when the cutout box is filled with oil. This cap serves the triple purpose: First, that of clamping the divided ends of the pigtail or flexible conductor 21 to the ferrule 19; secondly, that of venting the housing tube 15; and, third, that of catching the expelled parts so as to prevent them from causing an electrical contact with the metal parts of the cutout box.

Referring to the liquid or oil type of fuse cartridge shown in Fig. 3, it will be understood that the chamber 38 is filled with oil or other suitable arc extinguishing substance and that the oil is retained by the diaphragm 34 and by applying a lacquer or similar medium to the threads at the opposite end of the fuse cartridge.

In operation, when a predetermined over-current occurs, the fuse 30 melts or blows and establishes an arc which decomposes the surrounding oil, resulting in a pressure being built up in the chamber 38. The pressure, after reaching a predetermined value, will rupture the diaphragm 34 and establish a second arc in the orifice formed in the bushing 27. A blast of oil and gas into this second arc will interrupt the high voltage circuit in a quick and efficient manner similar to the operation of the dry tube previously described.

Where the liquid or wet type of fuse cartridge is employed, the cutout box will preferably be filled with oil so that the fuse device, together with the switch mechanism employed, will be completely submerged. In that case the circuit shunting device may be entirely eliminated as the switch blades and flexible contacts will be submerged in the oil and the arc formed when operating as a disconnect switch will be quenched thereby.

While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is:

1. In a circuit interrupting device, a member

having a chamber formed therein, a pair of terminal connectors, one at each end and insulated from the member, a circuit interrupting device disposed interior of the member between the terminal connectors and forming a conductor between one terminal connector and said member, said chamber forming a receptacle for an arc extinguishing medium, and said member forming a conductor between the other terminal connector and the interrupting device and sustaining the pressure produced during interruption of the circuit.

2. In a circuit interrupting device an elongated member having a chamber formed therein, said chamber forming a receptacle for an arc extinguishing medium, means at opposite ends of the chamber for forming successive arcs, said elongated member forming a conductor between the arc forming means and sustaining the pressure produced by the arc forming means, a pair of terminal connectors, one at each end of the elongated member and insulated therefrom, and a connection between each terminal connector and an adjacent arc forming means.

25 3. In a circuit interrupting device an elongated member having a chamber formed therein, said chamber forming a receptacle for an arc extinguishing medium, means at one end of the chamber for forming an arc, a terminal connector at each end of the elongated member and insulated therefrom, a connector between one terminal connector and the arc forming means, a connector between the other terminal connector and the adjacent end of the elongated member, said member forming a conductor between the last-named connection and the arc forming member and sustaining the pressure produced by the arc forming means.

4. In a circuit interrupting device a cutout box, a switch within the box having a pair of stationary and a pair of movable terminals, a fuse controlled circuit interrupting device connected between the movable terminals of the switch, metallic means for de-ionizing of gases discharging by the blowing of a fuse, and means for establishing a shunt circuit for preventing excessive arcing when disengaging the movable terminals of the switch with relation to the stationary terminals.

5. In a circuit interrupting device a cutout box, a switch within the box having a pair of stationary and a pair of movable terminals, a fuse controlled circuit interrupting device connected between the movable terminals of the switch, means for momentarily shunting the circuit when disengaging the terminals of the switch, and a resistance material in said shunt circuit, said material having the characteristic of becoming a relatively good conductor at an alternating current zero when an arc is drawn between the switch contacts and thereby shunt the current through the resistance material and reduce the arcing between the switch contacts.

6. In a circuit interrupting device, a metallic member within the device and having a chamber formed therein, and means in the chamber to form two arcs, said metallic chamber adapted to sustain the pressure generated by said arcs and to act as a conductor between the arcs and an arc extinguishing substance surrounding each arc.

70 7. In a circuit interrupting device, a metallic member within the device having a chamber formed therein, and means in the chamber for establishing a preliminary arc and thereafter a second arc, said metallic member acting as a

conductor between the arcs and an arc extinguishing substance surrounding each arc.

8. In a circuit interrupting device, a metallic member within the device having a chamber formed therein, and a compound fuse element having a small current carrying capacity section and a greater current carrying capacity section located within the chamber, said metallic member acting as a conductor between the two fuse sections.

10 9. In a circuit interrupting device, a metallic member within the device having a chamber formed therein, and a compound fuse element having a small current carrying capacity section and a greater current carrying capacity section located within the chamber, said metallic member acting as a conductor between the two fuse sections, said fuse element of greater current carrying capacity forming a seal for one end of the chamber.

15 10. In a circuit interrupting device, a metallic member within the device having a chamber formed therein, means in the chamber for establishing a preliminary arc and thereafter a second arc, said metallic member acting as a conductor between the arcs, and an arc extinguishing substance in the chamber and surrounding both arcs, said metallic member sustaining the pressure generated by the arcs, said arc extinguishing substance being blasted into the second arc by the pressure generated by the preliminary arc.

20 11. In a circuit interrupting device, a metallic member within the device having a chamber formed therein, a compound fuse element having a small current carrying capacity section and a greater current carrying capacity section located within the chamber, said metallic member acting as a conductor between the two fuse sections, and an arc extinguishing substance in the chamber and said metallic member sustaining the pressure generated within the chamber, the energy generated during the blowing of the small fuse section being utilized to aid in establishing an arc in the fuse of greater current carrying section.

25 12. In a circuit interrupting device, a metallic member within the device having a chamber formed therein, a compound fuse element having a small current carrying capacity section and a greater current carrying capacity section located within the chamber, said metallic member acting as a conductor between the two fuse sections, and an arc extinguishing substance in the chamber and said metallic member sustaining the pressure generated within the chamber, the energy generated during the blowing of the small current carrying section being utilized to aid in extinguishing the arc formed in the fuse of greater current carrying section.

30 13. In a circuit interrupting device of the character described an elongated metallic tubular member having a tapered seat formed at each end, a tapering insulator insertable and engageable with each seat, a terminal member carried by each insulator, and a fuse device connecting each terminal member with the metallic tube.

35 14. In a circuit interrupting device of the character described an elongated metallic tubular member having a tapered seat formed at each end, a tapering insulator insertable and engageable with each seat, a terminal member carried by each insulator, a cup-shaped contact member on the inner end of each insulator and seating in and engaging the metallic tube, and a fuse device connected with each terminal member and with an adjacent cup-shaped contact member.

15. In a circuit interrupting device of the character described an elongated metallic tubular member having a tapered seat formed at each end, a tapering insulator insertable and engageable with each seat, a terminal member carried by each insulator, one of said terminal members being expellable, and a fuse device connecting each terminal member with the metallic tube. 5
16. In a circuit interrupting device of the character described an elongated metallic tubular member having a tapered seat formed at each end, a tapering insulator insertable and engageable with each seat, a terminal member carried by each insulator, one of said terminal members being expellable, a fuse device connecting each terminal member with the metallic tube, and a packing means sealing one end of the tube and normally retaining the expellable terminal member against removal. 10
17. In a circuit interrupting device of the character described an elongated metallic tubular member having annular shoulders formed thereon adjacent opposite ends, fuse plugs insertable in the opposite ends of the tube, each plug having a contact end engageable with the adjacent shoulders, and a terminal member carried by each fuse plug to establish an electric circuit. 15
18. In a circuit interrupting device of the character described an elongated metallic tubular member having annular shoulders formed thereon adjacent opposite ends, fuse plugs insertable in the opposite ends of the tube, each plug having a contact end engageable with the adjacent shoulders, a terminal member carried by each fuse plug to establish an electric circuit, one of said annular shoulders having an annular tapering contracted passage formed therein to form a discharge orifice for the discharge of gases generated during blowing of the fuse at high velocity. 20
19. The combination with the expulsion end of a fuse of the character described, of a de-ionizing device comprising a container consisting of an inner and an outer housing, said housings being spaced apart and the walls of said housings being perforated and a de-ionizing medium disposed in the space formed between the housings. 25
20. The combination with an expulsion end of a fuse of the character described, of a de-ionizing device comprising a container consisting of an inner and an outer housing, said housings being spaced apart and the walls of said housings being perforated, and a metallic de-ionizing medium disposed in the space formed between the housings. 30
21. In a high voltage fuse, an expulsion tube having metallic end terminals, a re-fill cartridge for insertion in the tube, said cartridge comprising a metallic member within the cartridge, said member having a chamber formed therein, and means in the chamber to form an arc, said metallic member adapted to sustain the pressure generated by said arc and to act as a conductor between said arc and the terminals. 35
22. In a high voltage fuse, an expulsion tube having metallic end terminals, a re-fill cartridge for insertion in the tube, said cartridge comprising a metallic member within the cartridge having a chamber formed therein, means in the chamber for establishing a preliminary arc and thereafter a second arc, said metallic member acting as a conductor between the arc and an arc extinguishing substance in the chamber and said metallic member sustaining the pressure generated by the arcs. 40
23. In an enclosed high voltage cutout box, electric terminals within the box, an expulsion fuse comprising an insulating tube, a fuse element within the tube, a metallic de-ionizing and cooling means attached to the end of the expulsion tube, and means for connecting the expulsion fuse to the terminals within the box. 45
24. In a high voltage fuse, an expulsion tube having metal end terminals, a re-fill cartridge for insertion in the tube, said re-fill comprising a metallic tube having a chamber formed therein, means in the chamber for establishing an arc, and means in the chamber for interrupting the arc after it is established. 50
25. In a circuit interrupting device an enclosed cutout box, a switch within the box connected with a source of current supply, a fuse-controlled circuit interrupting device connected in the circuit and disposed within the box, and means for de-ionizing gases discharging by the blowing of the fuse, said means comprising a container consisting of an inner and an outer housing, said housings being spaced apart and the walls of said housings being perforated, and a de-ionizing medium disposed in the space formed between the housings. 55
26. In a circuit interrupting device an enclosed cutout box, a switch within the box connected with a source of current supply, a fuse-controlled circuit interrupting device connected in the circuit and disposed within the box, and means for de-ionizing gases discharging by the blowing of the fuse, said means comprising a container consisting of an inner and an outer housing, said housings being spaced apart and the walls of said housings being perforated, and a metallic de-ionizing medium disposed in the space formed between the housings. 60
27. In a circuit interrupting device an enclosed cutout box, a switch within the box connected with a source of current supply, a fuse-controlled circuit interrupting device connected in the circuit and disposed within the box, means for momentarily shunting the circuit when disengaging the terminals of the switch, a resistance material in said shunt circuit, said material having the characteristics of becoming a relatively good conductor at a high voltage and a poor conductor at a relatively low voltage when an arc is drawn between the switch contacts, and thereby shunt the current through the resistance material and reduce the arcing between the switch contacts. 65
28. In a circuit interrupting device an enclosed cutout box, a switch within the box connected to a source of current supply, a fuse-controlled circuit interrupting device connected in the circuit and disposed within the box, metallic means for de-ionizing gases discharging by the blowing of the fuse, and means for establishing a shunt circuit for preventing excessive arcing when disengaging the switch. 70
29. In a circuit interrupting device a member having a chamber formed therein, a pair of terminal connectors, a circuit interrupting device between the terminal connectors, said chamber forming a receptacle for an arc extinguishing medium, and said member forming a conductor between the terminal connectors and the interrupting device and sustaining the pressure produced during interruption of the circuit. 75
30. In a circuit interrupting device an elongat-

ed member having a chamber formed therein, said chamber forming a receptacle for an arc extinguishing medium, means at opposite ends of the chamber for forming successive arcs, said 5 elongated member forming a conductor between the arc forming means and sustaining the pressure produced by the arc forming means.

31. In a circuit interrupting device, a metallic member within the device, said member having 10 a chamber formed therein, and means in the chamber to form an arc, said metallic member adapted to sustain the pressure generated by

said arc and to act as a conductor between said arc and a terminal.

32. In a circuit interrupting device, a metallic member within the device, said member having a chamber formed therein, means in the chamber to form an arc, said metallic member adapted 5 to sustain the pressure generated by said arc and to act as a conductor between said arc and a terminal, and an arc extinguishing substance in the chamber.

GEORGE LESLIE HILL.
